THOMAS GRIST, OF PHILADELPHIA, PENNSYLVANIA.

Letters Patent No. 78,451, dated June 2, 1868; antedated May 19, 1868.

IMPROVEMENT IN REFLECTING GAS-BURNERS.

The Schedule referred to in these Letters Patent and making part of the same.

TO ALL WHOM IT MAY CONCERN:

Be it known that I, THOMAS GRIST, of Philadelphia, Pennsylvania, have invented an Improvement in Reflecting Gas-Burners; and I do hereby declare the following to be a full, clear, and exact description of the same, reference being had to the accompanying drawing, and to the letters of reference marked thereon.

My invention relates to an improvement in the gas-burners with which are combined spherical or oval reflectors; and my improvement consists, among other features, in arranging a burner on the top of the reflector, so that the upper portion of a room may be illuminated, as described hereafter.

In order to enable others skilled in the art to make my invention, I will now proceed to describe the construction of the same.

On reference to the accompanying drawing, which forms a part of this specification—
Figure 1 is an exterior view of my improved reflecting gas-burner,

Figure 2 a vertical section, and

Figures 3 and 4 sections of parts of my improvement, drawn to an enlarged scale.
Similar letters refer to similar parts throughout the several views.

A is a short tube, having internal screw-threads, adapted to similar threads on the tube of a gas-bracket or chandelier, and on to the tube A is screwed the hollow distributor B, from which project two or more small tubes, D, each terminating in a burner, a, a packing-ring, b, intervening between the tube A and distributor B.

A vertical pipe, E, is secured to and communicates with the interior of the distributor, and to the top of this pipe is secured the burner e.

F is a reflector, consisting, in the present instance, of a hollow sphere of glass, silvered on the inside, there being a hole at the top, and another at the bottom of the reflector, so that it may be placed over the vertical pipe E, and rest on a washer, h, which is loosely fitted to the top of the distributor B. Another washer, i, is placed over the pipe E, rests on the top of the reflector, and is confined thereto by the upper burner, e, which serves as a nut.

Reflectors of a spherical or oval form, combined with two or more gas-burners, have been in use in this country, and have been imported from abroad for several years past, but the burners have invariably been so situated as to reflect the light downwards, leaving the upper portion of the room comparatively dark, a defect obviated by the use of the upper burner, e, the light from which is so reflected as to illuminate the upper portion of the room.

It will be observed that the two washers, h and i, are perforated, and that the holes in the reflector, for the admission of the pipe E, are larger than the latter, so that the air can pass through the perforations of the lower washer, through the reflector, and through the perforations of the upper washer, thereby maintaining the reflector comparatively cool, and preventing it from being fractured by the heat from the burners.

I claim as my invention, and desire to secure by Letters Patent—

1. The arrangement of the burner e on the top of the reflector F, as and for the purpose set forth.
2. The combination of the distributor B, pipe E, passing through the reflector, and the burner e.
3. The perforated washers h and i, in combination with the pipe E, the reflector F, and the openings in the latter.

In testimony whereof, I have signed my name to this specification in the presence of two subscribing witnesses.
